[57] **CLAIM**

The ornamental design for a physical dynamometer, as
shown and described.

DESCRIPTION

FIG. 1 is a front perspective view of a physical dynamometer showing my new design;
FIG. 2 is a rear perspective view thereof;
FIG. 3 is a side elevational view thereof, the side opposite being substantially a mirror image; and,
FIG. 4 is an end elevational view thereof.

FIG. 1

FIG. 2

FIG. 3

FIG. 4
